W. A. HOUGHTALING

AUTOMATIC TELEGRAPH SYSTEM

Filed July 13, 1923

Patented Aug. 25, 1925.

1,551,500

UNITED STATES PATENT OFFICE.

WALTER A. HOUGHTALING, OF DUNELLEN, NEW JERSEY, ASSIGNOR TO THE WESTERN UNION TELEGRAPH COMPANY, OF NEW YORK, N. Y., A CORPORATION OF NEW YORK.

AUTOMATIC TELEGRAPH SYSTEM.

Application filed July 13, 1923. Serial No. 651,404.

To all whom it may concern:

Be it known that I, WALTER A. HOUGHTALING, a citizen of the United States, residing at Dunellen, in the county of Middlesex 5 and State of New Jersey, have invented certain new and useful Improvements in Automatic Telegraph Systems, of which the following is a specification.

This invention relates to improvements in 10 operating automatic telegraph systems on the well-known Baudot multiplex principle, and particularly to the method sometimes designated as the "fork and series" method. The principles of this method are described 15 in H. W. Pendry's book on "The Baudot Printing Telegraph System."

In the "fork and series" method of operation, the line impulses or telegraph signals are received at an intermediate station from 20 one line section and transmitted by means of a rotary repeater to the next section in regenerated impulses, free from distortion. The lines, of course, are duplexed so that 25 messages may be transmitted simultaneously in both directions through the repeater.

In prior systems of this character the repeater equipment has been complicated by the large number of relays required, one for each of the 20 segments of a four channel 30 circuit and a separate set of relays being required for each channel, together with locking and unlocking circuits for these relays. The purpose of my invention is to greatly simplify the equipment by an organization 35 which enables a single set of relays to function in each channel in succession and to entirely eliminate the locking circuits heretofore required.

The advantages of my improvements will 40 be comprehended from the following description in connection with the annexed drawing wherein the preferred embodiment is shown diagrammatically.

To illustrate the features of my invention 45 I have shown in the usual conventional manner, terminal stations A and C, equipped with rotary distributors RT and RT' and line relays M, M', duplexed as usual. The intermediate repeater station B is equipped 50 with a rotary receiving and transmitting repeater RT² and line relays M² and M³, connected respectively to the line sections L and L'.

I have shown the system arranged for a

"quad" or four channel operation. The segmented transmitting or sending rings s₁ and s₄ of the rotary distributors at the terminal stations having their four groups of five segments each, connected to the separate transmitters, as indicated, may be of the 55 type shown in U. S. patent to G. R. Benjamin No. 1,298,440. Likewise the groups of five segments each of the rings r₁ and r₄ may be connected in the usual manner to the 60 selecting magnets of separate printers. 65

At the repeating station B, I connect the corresponding segment of each set of five, i. e., the corresponding segment in each of the several channels, in multiple to one terminal of a polarized relay, the other terminal of 70 each relay being connected to a potentiometer p across the poles of a generator. The armature of each relay is connected in multiple to each of the corresponding segments of the several channels of the sending ring 75 which transmits or repeats into the next line section. The contacts which cooperate with the relay armatures are connected in multiple to a source of current g and g'. It will 80 be seen, therefore, that I employ only one set of five polar relays to receive and retransmit through all of the channels.

The operation will be readily understood 85 by telegraph engineers. The five-unit combinations of positive and negative impulses of the code characters impressed upon the segments of the transmitter ring s₁ by the separate tape transmitters, are picked up by the rotating brushes b and transmitted in succession to the line L. As the line relay M² at the repeater station responds to these 90 impulses, the corresponding positive and negative polarities are impressed upon the segments of the receiving ring r₂ of the rotary repeater RT², and as the brushes b₂ rotate in synchronism with the brushes b, 95 the same polarities will be impressed upon the polar relays PR.

The two transmitting rings s₂ and s₃ of 100 the repeater are adjusted on the shaft until the fourth segment on each of these rings is in alinement with the first segment of the receiving rings r₂ and r₃. This relation or relative position of the sending and receiving rings is indicated by the corresponding 105 numbers on the segments. Since each segment covers 18° of the ring, the armatures of the polar relays will have a period equal

to the time required by the brushes to pass over 36° in which to settle down in case there is any tendency to chatter between the time of receiving and transmitting an impulse. Thus an impulse impressed upon the first relay by the passage of brush b_2 over segment 1 of ring r_2 , causes the armature of the relay to swing against one or the other contact and thereby connect the segment 4 of ring s_2 with the generator g , but the impulse is not transmitted by the repeater to the line L' until the brushes have passed over two intervening segments, i. e., until they have reached the fourth segment. Each relay, however, transmits the impulse of one five-unit character before it receives the corresponding impulse of the next succeeding character.

Inasmuch as the line relays are connected in duplex arrangement, the characters sent by the A transmitter from station A will be received by the A printer at station C, simultaneously with the transmission of characters by the A transmitter of station C and which are received by the A printer of station A. The same operation takes place in the other channels of the multiplex.

At the repeater station, the characters sent from station A actuate the line relay M^2 and its armature impresses the corresponding impulses upon the segments of receiving ring r_2 and these are transferred to the polar relays PR. The tongues or armatures of these relays connect the segments of the sending ring s_2 with one or the other pole of the generator g , thus repeating the impulses regenerated into the line section L' . In the same manner the impulses received by the line relay M^3 sent out from station C, are transferred to the segments of the receiving ring r_3 , and from thence to the polar relays PR'. The armatures of those relays connect the segments of the sending ring s_3 with the generator g' and upon the passage of the brush b_4 the renewed or regenerated impulses are repeated to the line section L .

The distributors at the terminal stations and the rotary repeater at the intermediate station are rotated in synchronism, each being driven preferably by a motor of the La Cour phonic wheel type. The rotary repeater is corrected from the distributor at station A and distributor at station C is corrected from the repeater, the correction being effected automatically in the manner well understood by multiplex operators, by the correcting system disclosed in U. S. patent to Rothermel No. 1,253,889.

The number of channels working between any two stations may be varied within certain limits. Thus a "quad" or four channel circuit may be arranged to work all four channels between the terminal stations; or to work three channels between terminals

and one channel between the repeater station and each terminal; or to work two channels between terminals and two channels between the repeater and each terminal; or to work one channel between terminals and three channels between the repeater station and each terminal. In the diagram I have shown the three channels A, B and C working between the terminal, while on the channel D the operator at the repeater station has printers connected to receive from either station A or station C and transmitters connected to send messages to either terminal.

The channel D is, therefore, dropped at the repeater station from the series transmission in both directions, so that no messages are transmitted from either terminal to the other through the repeater on the D channel.

As pointed out above, the D channel can be used at the repeater station to receive messages on a printer connected to the segments 16 to 20 of the ring r_2 sent from the D transmitter at the A station. However, instead of connecting a printer at the receiving station, this channel may be connected to a printer located at some distant station on a branch line. Said distant station may also transmit messages simultaneously through the repeater station to the A station over the D channel by having the branch line connected to the segments 19, 20, 1, 2 and 3 of the ring s_2 .

In the same manner the messages over D channel operated by the D transmitter at the C station may be received by a printer at the repeater station connected to the segments 16 to 20 of ring r_3 , or these segments may be connected to a branch line and the printer may be located at a distant station on that line. Likewise the transmitter at that distant station may transmit messages simultaneously to the D printer at the C station if said branch line is connected to the segments 19, 20, 1, 2 and 3 of rings s_2 of the rotary repeater.

In the example shown, therefore, the multiplex system operates through the repeater station in series from station A to station C on three channels of the circuit and forks at the repeater station on the D channel to provide for the interchange of messages from the stations A and C to stations on other lines which branch off from the repeater station. The rotary distributors at the station on the branch lines will be maintained in synchronism by correcting from the rotary repeater at the repeater station.

While I have shown only the D channel forked at the repeater station to other lines, it is evident that other channels may be forked in the same manner to other branch lines.

I claim:—

1. In a telegraph system, a plurality of stations, a line divided into sections, a multiplex synchronous system connecting said stations, and a relaying apparatus interposed between adjacent line sections including a set of polarized relays operable by impulses received from one of the sections, said set being connected successively to each channel of the multiplex system, a source of energy for forming impulses for the next section, and circuit connections therefor controlled by said relays. 45
2. A telegraph system, comprising a line divided into sections, a plurality of stations, a multiplex synchronous system connecting said stations and including a relaying apparatus interposed between adjacent line sections, said apparatus comprising a rotary repeater having a pair of segmented rings and a set of polarized relays having the magnets connected in multiple respectively to the corresponding segments of each of the different channels of the multiplex system in one ring and the armatures connected in multiple respectively to the corresponding segments of the other ring, a branch line connected to the segments of said repeater rings of one channel and a station in said branch line having a printer and a transmitter operating synchronously with said repeater. 50
3. A telegraph system, comprising a line divided into sections, a plurality of stations, a multiplex synchronous system connecting said stations and including a relaying apparatus interposed between adjacent line sections, said apparatus comprising a rotary repeater having pairs of segmented rings, a source of energy, a plurality of sets of polarized relays, one set associated with each pair of rings and functioning successively with the segments of each channel of the multiplex to receive impulses from one line section and to transmit to another line section impulses derived from said source of energy and corresponding to said received impulses, branch lines connected to the segments of said repeater rings of certain channels and stations in said branch lines provided with printers and transmitters operating synchronously with said repeater. 55
4. A telegraph system, comprising a line divided into sections, a plurality of stations, a multiplex synchronous system connecting said stations and including a relaying apparatus interposed between adjacent line sections, said apparatus comprising a rotary repeater having a pair of segmented rings and a set of polarized relays having the magnets connected in multiple respectively to the corresponding segments of each of the different channels of the multiplex system in one ring and the armatures connected in multiple respectively to the corresponding segments of the other ring, a branch line connected to the segments of said repeater rings of one channel and a station in said branch line having a printer and a transmitter operating synchronously with said repeater. 60
5. A telegraph system, comprising a line divided into sections, a plurality of stations, a multiplex synchronous system connecting said stations and including a relaying apparatus interposed between adjacent line sections, said apparatus comprising a rotary repeater having pairs of segmented rings, a source of energy, a plurality of sets of polarized relays, one set associated with each pair of rings and functioning successively with the segments of each channel of the multiplex to receive impulses from one line section and to transmit to another line section impulses derived from said source of energy and corresponding to said received impulses, branch lines connected to the segments of said repeater rings of certain channels and stations in said branch lines provided with printers and transmitters operating synchronously with said repeater. 65
- In testimony whereof I affix my signature.

WALTER A. HOUGHTALING.
